UNITED STATES PATENT OFFICE.

CHARLES D. McDONALD, OF CHICAGO, ILLINOIS.

PROCESS OF APPLYING SANITARY LININGS TO CAN ENDS.

1,263,580.

Specification of Letters Patent. Patented Apr. 23, 1918.

Application filed February 23, 1917. Serial No. 150,444.

To all whom it may concern:

Be it known that I, CHARLES D. McDONALD, a citizen of the United States, residing at Chicago, in the county of Cook and State of Illinois, have invented certain new and useful Improvements in Processes of Applying Sanitary Linings to Can Ends, of which the following is a specification.

10 The present invention relates to a process of coating a sheet of material, preferably thin metal, in such manner to enable the production of lined sanitary can ends in a quicker and more economical manner than such ends have heretofore been produced.

15 The primary object of the invention is to take a sheet of metal, from which a number of sanitary can ends can later be produced, and to cover a portion of the surface 20 of this sheet with a lining composition, whereby when said ends are produced from said sheet, they will have a portion thereof lined with a sealing compound, which lining is characteristic of such ends.

25 A further object of the invention is to arrange the coating of lining composition upon the sheet of metal whereby undue waste of the same will not occur, and whereby the can end when produced will have a 30 lining positioned in a fashion similar to the linings now employed.

The invention further consists in the features of construction and combination of parts hereinafter described and claimed.

35 In the drawings:

Figure 1 is a face view of a sheet of metal having a lining compound applied to one surface thereof in accordance with the present invention;

40 Fig. 2, a detail showing a strip of metal severed from the sheet and of a character to be fed into the die-press for the production of can ends;

Fig. 3, an under face view of one of the 45 completed can ends; and

Fig. 4, a cross-section of the end shown in Fig. 3.

In the art to which the present invention relates, and connected with the manufacture 50 of cans, there is produced what is known as a sanitary can end. This can end is formed with a groove adjacent its outer edge, in which is placed a sealing compound or a paper gasket, which will tend to prevent leakage of air, etc., when the can end 55 is assembled to the can body.

In the present invention, it is intended, at a single operation, to place the lining composition upon the material, so that the liner for a plurality of said ends is applied 60 at one operation, and so far as the lining is concerned, no further steps are required from then on, the lining material being so positioned that when the end is formed it will be properly positioned thereon. 65

Referring to the drawings, the invention is shown in conjunction with a sheet of metal 5, which, as illustrated, is of rectangular formation, having side edges 6, a top edge 7, and a bottom edge 8. The use of 70 the terms "side", "top" and "bottom" are for descriptive purposes only, and are used in conformity with the way the sheet of metal is positioned in the drawings, and no other limitation than the above is intended 75 by these terms.

The sheet of metal is subjected to the action of a lithographing press, or otherwise, to place upon a portion of one surface thereof, a coating of liner composition 9. This 80 composition may be of any suitable form, and a formula which is adapted to produce a suitable composition is as follows:

Calcium carbonate (whiting) -	80 per cent.
Iron oxid -	5 per cent.
Rosin -	15 per cent.

As stated, the above formula is the most suitable for practising the invention, of which I am aware, but, of course, the invention is not intended to be limited in any way to the use of a substance having the formula specified. 90

In placing the composition upon the sheet, certain portions 10 of the sheet are left uncovered. These portions form spaces which occur at regular intervals in lines extending from side to side of the sheet, and said lines occur at regular intervals from the top to the bottom edge of the sheet. These uncovered portions 10 will form the center of the can end when said end is formed by the action of the die-press. It is not desirable or necessary to line the entire inner surface of the end, and by placing the coating upon the 100 sheet in the manner described, the ends when formed will have the lining material only along the inner surface of the outer groove, as is customary. 105

After the sheets have been treated as 110 above, and the liner compound applied, they are placed in a shearing machine, of

the character embodied in my Patent No. 1,174,747, issued March 7, 1916, and entitled Metal shearing machines, or are otherwise cut to produce elongated strips 11 of the general nature shown in Fig. 2. These strips are fed into the die-press and the die acts to cut the can ends out therefrom. The cuts of the die-press are shown by means of the dotted circles 15, and, as will be seen, 10 the lined portions of the material extend around the outer portion of the cut parts.

The strip illustrated in Fig. 2 is of the form which would be produced through the cutting of the sheet by the shearing machine 15 disclosed in the above-described patent, but, of course, the size and configuration of the strip could be varied without departing from the present invention. The ends 12, which are produced from the strip 11, are 20 of the character shown in Figs. 3 and 4, and comprise a depressed center portion 13, surrounding which is a groove or channel 14, which is lined with the sealing substance 9.

Referring back to Figs. 1 and 2 and comparing them with Fig. 4, it will be very apparent how, by placing a liner substance on the surface of the sheet of metal in the manner described, said sheet when subjected to the action of a die-press to produce the can 25 ends will produce an end which will have the lining substance positioned within the outer groove thereof, and will therefore have the lining positioned in conformity to the linings of the standard form of sanitary 30 can ends.

It will also be apparent that by the single lithographing operation which places the liner substance on the sheet 10, the lining for a plurality of can ends is placed in position 40 at a single and relatively quick operation.

After placing the compound upon the surface of the sheet, the said sheet can be subjected to a baking operation to firmly set the compound in position; and the compound is 45 of such a nature that when baked, it will not be hard to the extent that it will crack under the effect of the action of the die in forming the can end, and at the same time it will be sufficiently hard so that it will not 50 scrape off by handling the sheets in cutting

them up into strips and feeding the strips through the die-press.

If it is found that one coating of the lining substance does not make a lining sufficiently thick for the work intended, a second coating can be readily applied after the first one has dried. Thus, the character of the lining can be adapted as desired to particular forms of work.

I claim:

1. The process of applying sanitary linings to can ends, which consists in taking a sheet of metal and applying a sanitary lining substance in liquid form thereto, said substance being applied in a manner to 65 cover a part of one surface of said sheet, the uncoated portion of said surface being of circular formation and occurring at regular intervals in lines extending from one edge of the sheet to the other, with the uncoated 70 portions in one line arranged in staggered relation to the uncoated portions in the next line, then cutting the sheet to produce a plurality of can ends therefrom with the uncoated 75 portions positioned at the center of the ends and the coated portions at the outer edge thereof, substantially as described.

2. The process of applying sanitary linings to can ends, which consists in taking a sheet of metal and applying a sanitary lining substance in liquid form thereto, said substance being applied in a manner to 80 cover a part of one surface of said sheet, the uncoated portions of said surface being of circular formation and occurring at regular 85 intervals in lines extending from one edge of the body to the other with the uncoated portions of one line being in staggered relation to the uncoated portions in the next line, then cutting the sheet in undulating 90 lines of cut extending between the lines of uncoated portions to form a series of elongated scroll-edged strips, then cutting said strips to produce a plurality of can ends 95 therefrom, with the uncoated portions positioned at the center of the ends and the coated portions at the outer edge thereof, substantially as described.

CHARLES D. McDONALD.
